Inventor:

Geo Richardson

United States Patent Office.

GEORGE RICHARDSON, OF LOWELL, MASSACHUSETTS.

Letters Patent No. 90,958, dated June 8, 1869.

IMPROVED STEP AND BEARING FOR VERTICAL SHAFTS.

The Schedule referred to in these Letters Patent and making part of the same.

To all whom it may concern:

Be it known that I, GEORGE RICHARDSON, of Lowell, in the county of Middlesex, in the State of Massachusetts, have invented a new and improved Step and Bearing for Vertical Shafts; and I do hereby declare that the following is a full, clear, and exact description of the construction and operation of the same, reference being had to the annexed drawings, making a part of this specification, of which—

Figure 1 is an elevation, and

Figure 2, a vertical section through the centre of the step B and upper bearing A, showing the shaft in position, and referring to the several parts by the letters of reference marked thereon.

To enable others skilled in the art to make and use my invention, I will proceed to describe its construction and operation.

My invention consists in providing a more perfect and simple step and bearing for the vertical shafts of machinery, as, for instance, the shafts of several kinds of water-wheels, where vertical shafts convey power from story to story of a mill, and all high-speeded and hard-working vertical shafts employed in manufacturing-establishments. In these cases, it often occurs that the entire weight of wheel, shaft, and attached gears and pulleys, is required to be borne by a single step at the lower extremity of the shaft; and, when the latter revolves, as is usual, at considerable speed, these steps and bearings will always cause trouble from friction, unless they be constantly lubricated, and otherwise attended to.

The construction and operation of my invention are as follows:

The step B, or bearing for the end of the shaft, is hollowed out at its upper part, to form a cavity, E, surrounding the shaft, for the purpose of containing the lubricating-fluid and its conductor.

The sides of this cavity, at its upper part, are brought in or contracted toward the centre, to form a top or cover, as shown at D, merely allowing sufficient space around the shaft C for the introduction of the lubricating-fluid. This guards the cavity E from dirt, or other foreign substances which might otherwise fall into it, and obviates the necessity of a separate movable cover.

The inner and central portion of the cavity, immediately around the shaft, forms an elevated edge or lip, G, whose outer sides incline down and back from the shaft, in all directions, to the bottom of the cavity E,

as shown. This forms a retaining-space for the lubricating-fluid.

Within the cavity E is a ring or circle, F, of felt, or similar porous material, of sufficient depth to embrace the shaft above the lip G, while its lower part is immersed in the lubricant contained in the lower part of the cavity E.

This felt need not embrace the shaft so tightly as to revolve with it. All that is intended is sufficient contact to keep the shaft moistened with the lubricant, which is drawn up by the capillary attraction of the felt.

The office of the inner elevated edge or lip G is not only to form a retaining-space for the lubricant, but to catch any gritty matters, or particles of abrasion, which may be formed in the bearing, whence the motion of the shaft will bring them up to the edge of the lip G, down the outer side of which they will flow, and settle at the bottom of the cavity; and, as it will be impossible for them to be drawn up thence by the capillary attraction of the felt, or porous conductor, they cannot come in contact with the working-surfaces again, and will thus be prevented from doing any injury. In common forms of bearing, such particles remain mingled with the lubricating-substance upon the bearing, and thus contribute to the wear of the working-surfaces.

The upper bearing A differs from the step B only in permitting the shaft to pass entirely through it. In all other essential respects, they are identical.

What I claim as my invention, and desire to secure by Letters Patent, is—

1. The cavity E, in the step B, and upper bearing A, for a vertical shaft; that is, having the upper portion of the sides of the cavity E contracted, or brought in toward the shaft, to form a top or cover for the cavity; also, having an elevated edge or lip, G, raised from the bottom of the cavity, and surrounding the shaft, all arranged substantially as described, and for the purposes set forth.

2. The ring or circle F, of felt, or other similar porous material, placed within the cavity E, in combination with the shaft and steps A and B, substantially as and for the purpose set forth.

GEO. RICHARDSON.
